UNITED STATES PATENT OFFICE

ARTHUR R. MORFORD, OF KOKOMO, INDIANA

PLASTERER'S FLOAT

Application filed December 16, 1929. Serial No. 414,446.

This invention relates to an improved tool or implement which is known in the trade as a float, the same being expressly intended for use by plasterers and analogous tradesmen.

As a general rule, a float of this class is somewhat in the nature of a block-like brush. It includes a handle and a backing member and a head carried by the backing member. The head is usually of different classes of material. In many instances for special work, the head is in the nature of a block of rubber.

It is a matter of common knowledge, however, that it is difficult to securely fasten the rubber to the backing member since the backing member is usually of metal (preferably aluminum) and it frequently happens that the rubber head will break loose from the backing member within the course of a few hours time and will seldom last over a day or two.

The novelty of this invention is predicated upon two features; namely, a method and means for fastening the rubber head to the metallic backing member, and the provision of a detachable handle with practicable means for separably connecting the end portions of the handle with the end portions of the backing member.

In the drawings:

Figure 1 is a top plan view of the improved tool.

Figure 2 is an edge or side elevation of the same.

Figure 3 is an enlarged fragmentary sectional view showing certain of the details.

As seen in Figures 1 and 2, the reference character 4 designates the metallic backing plate. This is in the nature of a substantially rectangular aluminum plate of appropriate thickness and it will be observed that the opposite ends thereof are bent laterally upward as at 5 and the extremities are turned down as at 6 to provide retaining flanges. This provides an intervening web as at 7.

The features 5, 6, 7 form hook-like keepers at the opposite ends of the backing plate.

These keepers are adapted for reception of

the foot-like extensions 8 on the opposite end portions of the handle 9. These extensions are widened out to render them of a length commensurate with the hook-like keepers at the opposite ends of the backing plate. In the top surfaces thereof I provide grooves, and the grooves removably receive the downturned flanges 6. Thus, the flanges 6 are in the nature of retaining keys and the grooves in the nature of keyways slidably receiving the keys.

At alternate ends the keyways are widened out somewhat to form pockets for reception of the removable retaining wedges 10. The wedges are of the end elevation configuration shown in Figure 2. When the wedges are driven into place, they bind the flanges 6 firmly in place, thus providing an unusual detachable connection between the handle and the backing plate.

This arrangement equalizes stress and strain, and at the same time affords a dependable detachable joint. The reversed arrangement of the wedges at opposite ends of the foot-like extensions as shown in Figure 1 is a feature to be emphasized since it insures uniform and equalized retaining means.

In accordance with the present invention, the backing plate is provided with a retention screen as at 11 in Figure 3. This is secured by solder or the like 12 to the plate and is imbedded in the adjacent surface of the rubber block-like head or surfacing member 13. It has been found sufficient, however, to simply solder the screen member to the backing plate and to then glue the screen member to the rubber block-like element 13. This provides a dependable joint between the elements.

The gist of the invention, it is to be understood, is in the arrangement of having the reversely arranged wedge-shaped keys removably receivable in the correspondingly shaped keeper grooves on the foot-like extensions 8 of the handle, together with the rubber block-like surface member or head 13, and the soldered screening for holding it in place.

Persons skilled in the art to which the in-

vention relates will be able to obtain a clear understanding of the construction, features and advantages, after considering the description in connection with the drawings.

6 Therefore, a more lengthy description is regarded as unnecessary.

Minor changes in shape, size and rearrangement of details coming within the field of invention claimed may be resorted to in
10 actual practice if desired.

I claim:

In a structure of the class described, in combination, a brush-head including a backing plate, having its opposite ends bent upwardly and its terminal portions bent downwardly to provide retaining flanges and intervening connecting webs, a handle including feet at its opposite ends resting firmly against said backing plate and having enlarged handle extensions provided with grooves constituting keyways and receiving said flanges, alternate end portions of the respective grooves being widened to provide wedge-receiving recesses and retaining
20 wedges fitted removably in said recesses and engaging a portion of the companion flange to securely and detachably fasten the handle to the backing plate.

In testimony whereof I affix my signature.

30 ARTHUR R. MORFORD.
